UNITED STATES PATENT OFFICE

LEE S. CHADWICK, OF SHAKER HEIGHTS, OHIO, ASSIGNOR TO PERFECTION STOVE COMPANY, OF CLEVELAND, OHIO, A CORPORATION OF OHIO

AIR PUMP FOR PRESSURE FUEL TANKS

Application filed January 13, 1927. Serial No. 160,846.

This invention relates to improvements in the class of liquid fuel stoves wherein the fuel is fed by air pressure, and it has to do more particularly with unique features pertaining to the pump by means of which air under pressure is injected into the fuel tank. In the present instance I have shown the invention associated with a stove of the same type as those disclosed in applications Serial Nos. 126,366 and 149,353, filed jointly by Marc Resek and myself on August 2, 1926 and November 19, 1926, respectively, and in an application bearing Serial No. 152,356, filed by said Marc Resek on December 3, 1926.

In stoves of the type referred to the pumps by which air pressure is created in the fuel tanks are separate from the stoves and have to be held with one hand, with their discharge openings or nozzles pressed firmly against the seats designed to receive them, while being operated with the other hand. The frame structures of stoves of the class in question are usually built principally or entirely of sheet metal and therefore are relatively light and yield more or less to any force, and because of this it is especially difficult to maintain a fluid tight connection between the outlet of the pump and the seat surrounding the air inlet of the stove while operating the pump.

Furthermore, manually operated valves, in addition to check valves, are employed for positively closing the air passageways of the tanks wherewith the pumps are adapted to be connected thereby to effectively prevent leakage of air after the operation of the pumps has been stopped and the pumps removed.

The objects of my invention are to provide means for supporting and properly positioning the pump with respect to the air inlet of the tank; to provide means, preferably in the nature of a spring latch, for detachably connecting the pump to the stove structure with its outlet opening or nozzle in fluid tight connection with the air inlet; to provide a valve, preferably in the nature of a screw valve, for positively closing the air inlet and which is adapted to assume driving connection with a part of the pump when the pump is posi-

tioned in operative relation to the stove and which is adapted to be manipulated through the intervention of the pump; and, more generally, to provide a simple, relatively inexpensive, substantial and durable construction through which the previously mentioned objects are attained.

An embodiment of the invention is illustrated in the accompanying drawings wherein Fig. 1 is a fragmentary sectional front elevation of a stove incorporating my improvements; Fig. 2 is a partial end elevation of the stove; Fig. 3 is an enlarged sectional detail through the connections between the pump and the fuel tank; Fig. 4 is a sectional detail on a further enlarged scale through the separable connection between the pump and the air inlet of the stove, and Fig. 5 is a section on the line 5—5 of Fig. 4.

The stove structure involves a top 1, an end panel 2 and a burner pan 3, the latter being connected to the end panel a suitable distance below and parallel with the top 1. The top 1 is provided with the usual burner openings, one of which is shown at 4 above a burner 5 (Fig. 1). A part or unit 6 is secured to and projects laterally from the end panel 2 in about the plane of the burner pan 3 and at its outer end is formed with a depending boss 7 that is surrounded by a depressed seat 8 to which a washer 9 of suitable packing material is applied. The boss 7 is designed to fit within the neck 10 of the fuel tank 11. Encircling the neck 10 is a band 12 having opposed trunnions 13 on which are pivoted the opposite ends of a bail 14. A screw 15 is threaded through the central portion of the bail and bears at its end within a depression that is formed in the upper side of the unit 6, and by the manipulation of the screw 15 the tank is adapted to be drawn up with its neck firmly engaged against the washer 9 thereby to effect a fluid tight connection between the tank and the unit 6. The screw 15 is equipped with a large head 16 that provides a comfortable hand grip for operating the screw and for carrying the tank when the latter is removed from the stove which obviously is effected by the retraction of the screw and the swinging of the bail 14 from

over the end of the unit 6 and allowing the tank to drop thereby to withdraw its neck from the boss 7.

While this feature comprises no part of my present invention I may explain briefly that a passageway 20 is formed in the unit 6 and communicates at one end with a tube 21 that is inserted upwardly into a counter-bore of the passageway 20 and extends to near the bottom of the tank. The opposite end of the passageway 20 connects with a conduit 22 that incorporates a valve 23 and leads to a retort or generator 24 that is removably secured to the conduit through means of a clamp 25. This removable retort constitutes the subject matter of a co-pending application of Marc Resek and myself, Serial No. 152,798, filed December 6, 1926. As may be seen by reference to said application the retort 24 discharges into a mixer which forms a part of a conduit leading to the burner 5.

The unit 6 incorporates a forwardly projecting arm 28, and a duct 29 leads through this arm and the adjacent body portion of the unit and downwardly through the boss 7, as shown in Fig. 3, for communication with the interior of the tank above the maximum liquid fuel level therein. The outer end of the duct opens into an enlargement 30 into which is shrunk, brazed or otherwise secured the reduced lower end of a fitting 31 whose upper end is enlarged and formed with a cavity 32. The fitting 31 has a central bore or passageway that is threaded at its upper end for the reception of a screw valve 33 whose lower end is designed for cooperation with a seat provided on the upper side of a restriction 34 that is formed about the bore of the fitting intermediate its ends. The opposite side of the restriction is tapered to form a seat for a ball check valve 35 that is retained within the lower portion of the bore by lugs 36. The screw valve 33 is provided with a bore or passageway 37 that opens at its lower end through a port 38 into the bore of the fitting 31 above the restriction 34; and at its upper end the passageway 37 is flared to provide a tapered seat 40 for the rounded end of the outlet extension or nozzle 41 of an air pump 42. This air pump is of common construction and principle and, excepting for the fact that its air outlet or nozzle 41 is formed with a hexagonal portion 43, and a circumferential groove 44 extends about the lower end of its barrel, it may be of usual form. A flange 45 surrounds the upper end of the screw valve 33, and rising from this flange about the seat 40 is a socket member 46 that is made of a size and shape to receive with a proper fit the hexagonal portion 43 of the pump nozzle 41.

It will be seen from the construction just described that when the nozzle of the pump is inserted into the socket 46 so as to engage the terminal of the nozzle with the seat 40 a

driving connection is effected between the pump and the screw valve 33 which will enable the valve to be manipulated by simply turning the barrel of the pump. The screw valve is prevented from withdrawal from the bore of the fitting 31 by the engagement of the flange 45 with a stop ring 48 that is set within the top of the cavity 32 and secured to the surrounding wall of the fitting by brazing or other means.

The proper angular relation between the pump and the fitting 31 is effected by means of a guide and support for the upper end of the pump barrel and in the present instance this is in the form of a sleeve 50 incorporated in a bracket 51 whose base 52 is secured by rivets or other fastening means 53, 54 and 55 to the end panel 2. The fastening means 55 is shown as being the same as that which secures the upper end of the fuel conduit 22 to the end panel. The bracket 51 is preferably formed from a single piece of strap metal.

The pump 42 is adapted to be maintained with its nozzle in substantially air tight contact with the seat 40 of the fitting 31 by a spring latch 56 that is shown in the present instance as being constructed from a piece of strap metal. The strap is inserted through a slot 57 in the end panel 2 and is carried up adjacent the inner side of the panel to where its upper end is secured to the panel by the previously mentioned fastening means 54. The lower end of the latch 56 is formed to fit the circumferential groove 44 of the pump barrel, and when the pump is projected downwardly through the sleeve 50 and its nozzle inserted into the socket 46, the groove 44 is presented in operative relation to the latch and the latch automatically springs into the groove and holds the pump against retraction. The pump is of the cylinder and piston reciprocating type and a knob or handle 58 by means of which the pump is operated is carried directly by the upper end of the piston rod 59.

To remove the pump from the stove it is only necessary to spring the latch 56 away from the pump barrel thereby to disengage its lower end from the groove 44 and withdraw the pump barrel from the sleeve 50; and to facilitate the disengagement of the latch from the pump a finger piece 60 is applied to the rear side of the latch, and formed integral with the finger piece is a stop 61 which is arranged to engage the panel 2 and thus prevent undue movement and a possible consequential permanent distortion of the latch.

While the manner of using the invention is evident from the foregoing description, I may explain, briefly, that when it is desired to inject air under pressure into the tank 11 the pump is inserted through the sleeve 50 and its nozzle is engaged within the socket 46 and pressed down until the terminal of the

nozzle contacts with the seat 40 whereupon the latch 56 will spring into the groove 44 and hold the pump in such position. The pump barrel is then rotated to retract the 5 screw valve 33 from its seat and this slight elevation of the valve will enhance the fluid tight connection between the pump nozzle and the seat 40, and the holding engagement of the latch with the shoulder provided by 10 the lower side of the groove 44. The pump is then operated, and when the desired pressure is obtained, as will be indicated by an air gauge 65 that communicates with the interior of the tank in a manner substantially identical with the communication established between the pump and the tank, the screw valve 33 may be lowered to its seat by a reverse rotation of the pump barrel and the air pressure will thus be positively held. The ball check 20 valve 35 functions to prevent escape of air during receding strokes of the pump piston.

For claim purposes, the tank 11 may be considered a receiver.

Having thus described by invention, what 25 I claim is:—

1. In combination with a receiver, an air pump, a ported part to which said pump is adapted to be applied for transmitting air from the pump to the receiver, a rotatable 30 valve controlling the passage of air through the port of said part, means supporting the pump for rotation with its discharge opening in communication with said port, and further means releasably holding the pump 35 in such position and in such manner as to permit of its being rotated, the pump and said valve having cooperating parts through which a driving connection is effected between the pump and valve whereby the valve is adapted to be rotated through the instrumentality of the pump.

2. In combination with a receiver, an air pump comprising a cylindrical barrel, said barrel having a circumferential shoulder, a 45 ported part to which said pump is adapted to be applied for transmitting air from the pump to the receiver, a rotatable valve controlling the passage of air through the port of said part, means embracing the barrel of 50 the pump for rotatably supporting the pump with its discharge opening in communication with said part, and a latch engaging the aforesaid shoulder for releasably holding the pump in such position, the pump and said 55 valve having cooperating parts through which a driving connection is effected between the pump and the valve whereby the valve is adapted to be rotated through the instrumentality of the pump.

60 3. In combination with a receiver, an air pump comprising a cylindrical barrel that is provided with a circumferential groove, a ported part to which said pump is adapted to be applied for transmitting air from the 65 pump to the receiver, a rotatable valve con-

trolling the passage of air through the port of said part, a supporting member incorporating a guide through which the pump barrel is adapted to be extended and by which said barrel is encircled, said guide serving to support the pump with its discharge opening in communication with said port, a latch having a part engaging within the aforesaid circumferential groove for releasably holding the pump in such position, the pump and said valve having cooperating parts effecting a driving connection between the pump and valve whereby the valve is adapted to be rotated through the instrumentality of the pump.

4. In combination with a receiver, an air pump comprising a cylindrical barrel having a circumferential groove, a ported part to which said pump is adapted to be applied for transmitting air from the pump to the receiver, a rotatable valve controlling the passage of air through the port of said part, a member incorporating a guide sleeve through which the barrel of the pump is adapted to be projected and serving to support the pump with its discharge opening in communication with said port, a spring latch arranged to engage the circumferential groove of the pump barrel and releasably holding the pump in such position, the pump and said valve having cooperating parts effecting a driving connection between the pump and valve whereby the valve is adapted to be rotated through the instrumentality of the pump.

5. In combination with a structure involving a panel and a receiver, an air pump comprising a cylindrical barrel having a circumferential groove adjacent its discharge end, a ported part to which the pump is adapted to be applied for transmitting air from the pump to the receiver, a rotatable valve controlling the passage of air through the port of said part, a bracket applied to the panel and involving a sleeve through which the barrel of the pump is adapted to be projected and serving to support the pump with its discharge opening in communication with the aforesaid port, a spring latch having a part disposed on the side of the panel remote from said bracket, the panel having an opening through which a part of said latch extends for engagement with the circumferential groove of the pump barrel, the pump and said valve having cooperating parts effecting a driving connection between the pump and valve whereby the valve is adapted to be rotated through the instrumentality of the pump.

6. In combination with a structure involving a panel and a receiver, an air pump comprising a cylindrical barrel having a circumferential groove adjacent its discharge end, a ported part to which the pump is adapted to be applied for transmitting air from the
